DESIGN.

—o—
F. MANKEY.

PANEL.

No. 16,236.

Patented Sept. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,236, dated September 8, 1885.

Application filed July 18, 1885. Term of patent 7 years.

To all whom it may concern:

Be it known that I, FREDERICK MANKEY, of Williamsport, Lycoming county, Pennsylvania, have invented a new and original Design for Surface Ornamentation of Walls, &c., the same consisting of a panel, of which the following is a specification, reference being had to the accompanying photograph, forming part hereof.

10 My design consists in rectangular elevations A, having rounded beveled edges formed in longitudinal rows upon the surface, the said elevations in each row being separated from each other by spaces or channels B. Upon 15 each elevation is shown a circular figure, C; but any other ornamental device may be substituted. The elevations A of the several longitudinal rows are staggered—that is, the elevations of one row are placed opposite the 20 spaces in the adjacent rows. There is no longitudinal channel between the rows, the elevations being brought into close contact at their edges which stand longitudinally the panel, which edges so in contact are not rounded or 25 beveled, as are the other edges.

I claim—

1. The design for a panel, substantially as herein shown and described, which consists in rectangular elevations A, disposed in rows longitudinally the panel, with intervening 30 channels, B, the elevations of adjacent longitudinal rows being in contact, and the elevations of one row being opposite the channels between the elevations of the next adjacent row.

2. The design for a panel, substantially as herein shown and described, consisting in rectangular elevations A, disposed in rows longitudinally the panel, with intervening channels, B, the elevations of adjacent longitudinal rows being in contact, and the elevations of one row being opposite the channels between the elevations of the next adjacent row, and on each elevation an ornamental figure, such as C.
